The ornamental design for a headboard, as shown and described.

DESCRIPTION

FIG. 1 is a perspective view of a headboard showing my new design; the opposite side being a mirror image thereof; and, FIG. 2 is a front elevational view.

The broken line showing of the bottom edge of the headboard defines the boundary but forms no part of the claimed design. The broken line showing of the two vertical supports is for environmental purposes only and forms no part of the claimed design.
